UNITED STATES PATENT OFFICE.

EDWARD J. BRANDT, OF WATERTOWN, WISCONSIN, ASSIGNOR TO BRANDT CASHIER COMPANY, OF CHICAGO, ILLINOIS.

COIN-DELIVERY MACHINE.

1,129,063.

Specification of Letters Patent. Patented Feb. 23, 1915.

Application filed July 30, 1914. Serial No. 354,048. **RHISSTUD**

To all whom it may concern:

Be it known that I, EDWARD J. BRANDT, a citizen of the United States, and resident of Watertown, in the county of Jefferson and State of Wisconsin, have invented certain new and useful Improvements in Coin-Delivery Machines; and I do hereby declare that the following is a full, clear, and exact description thereof.

Referring to coin-delivery machines of the "Brandt automatic cashier" type, the present invention has for its main object to provide against an operation of a coin-pusher of such a machine when there is less than a predetermined number of coins in a coin-tray compartment across the bottom of which said pusher is reciprocative, and said invention consists in what is herein particularly set forth with reference to the accompanying drawings and pointed out in the claims of this specification.

Figure 1 of the drawings represents a partly sectional elevation of an assemblage of parts in a coin-delivery machine of the type aforesaid; and it illustrates the automatic stop-mechanism herein specified; Fig. 2, a plan view of a detail of said mechanism partly in section indicated by line 2-2 in Fig. 1, and Fig. 3, a partly sectional view indicated by line 3-3 in said Fig. 1.

Referring by numerals to the drawings, 4 indicates a compartment of the coin-tray of a coin-delivery machine embodying my improvements, and the usual bottom slot 5 of the tray compartment is intersected by a rear wall slot 6 of said compartment in register with a slot 7 in a front plate 8 of the machine casing, said slot 6 being extended through a depending lug 9 of a reinforcing bar 9 on the back of said tray.

A stationary rod 10 in the machine constitutes a pivot engaging an offset bearing lug 11 of an elbow-rocker constituting a stop in one position of its adjustment, and a branch 12 of the rocker is fashioned to form a nose 12' engageable with the slots 6 and 7 aforesaid, and which at times extends into the coin-tray compartment over coin therein. The other branch 13 of the elbow-rocker constitutes an inclined lever, and said rocker is shown made of a pair of parallel pieces riveted together. When thus made, its lever-branch 13 is provided

with right-angle lateral flanges 13' to increase the upper bearing surface and rear end stop surface thereof. The bearing lug portions of the two piece elbow-rocker are angularly bent, and stems 14 hooked therein extend down through a notch in a flange 15' of a plate 15 fastened in the machine. The bearing-lug of said rocker engages a notch in an upper flange 15" of the plate 15, whereby it is held in place on the pivot-rod 10.

Surrounding the stems 14 between the bearing-lug 11 of the rocker and the lower flange of the plate 15 is a spiral-spring 16 under compression, and upward tilt of said rocker is limited by an opposing ledge of the machine frame.

As shown in Fig. 1, the depletion of the compartment of the coin-tray has permitted an automatic upward tilt of the elbow-rocker, its nose end being then over against a coin 17 in said tray-compartment and its lever end in the path of a clip 18 astraddle of the lower end of a spring-controlled swing-arm 19 in the machine to prevent coin-ejecting play of the spring-controlled coin-pusher 20 in pivotal connection with said arm, there being a play-slot 20' in said pusher engaged by the hook-branch of the elbow-rocker. A split-sleeve shank 18' of the clip 18 embraces a link-rod 21 coupled to a crank 22 of another rocker 23 on which a spring-controlled key-plate 24 of the machine is operative.

When the coin-compartment of the tray is not depleted to one or more coin, as may be predetermined, the elbow-rocker is automatically tilted by the opposing column of coin to have its inclined lever-branch under the joint of the swing-arm 19 and link-rod 21, which joint rides on the incline of said stop when said arm is swung to effect coin-ejecting play of the coin-pusher 20. The riding of the joint aforesaid on the depressed inclined lever-branch of the elbow-rocker operates to effect a further back-tilt of said rocker, whereby its nose 12' is swung clear of any and all coin opposed thereto, so as not to interfere with gravity descent of said coin in the tray-compartment.

The preferred construction and arrangement of parts herein shown is such that friction and power to operate the elbow-

rocker is minimized, and it is virtually an end of the swing-arm 19 that the lever end of said rocker opposes.

I claim:

- 8. 1. In a coin delivery machine, a coin-pusher swing-arm, and a spring-controlled elbow-rocker one branch of which is an inclined lever serving alternately as a track and stop for the swing-arm, its other branch being fashioned to provide a nose engageable with a rear wall slot of a coin-tray compartment of the machine to at times extend into said compartment over against coin therein, the rocker being then a stop in the forward path of said swing-arm.
- 10. 2. In a coin-delivery machine, a coin-pusher swing-arm, a pivot-rod, and a spring-controlled elbow-rocker having a bearing-lug loose on the rod, one branch of the rocker being an inclined lever serving alternately as a track and stop for the swing-arm, the other branch of said rocker being fashioned to provide a nose engageable with a rear wall slot of a coin-tray compartment of the machine to at times extend into said compartment over coin therein, the rocker being then a stop in the forward path of said swing-arm.
- 15. 3. In a coin-delivery machine, a coin-pusher swing-arm, an elbow-rocker one branch of which is an inclined lever serving alternately as a track and stop for the swing-arm, its other branch being fashioned

to provide a nose engageable with a rear wall slot of a coin-tray compartment of the machine to at times extend into said compartment over against coin therein, the rocker being then a stop in the forward path of said swing-arm; and a spring opposing the rocker from below.

40. 4. In a coin-delivery machine, an elbow-rocker comprising a pair of partly angularly bent and connected parallel pieces having right-angle flanges at one end constituting a track and stop alternately in the path of another movable part of the machine.

45. 5. In a coin-delivery machine, a rocker-stop having an inclined lever branch that serves alternately as a track and stop for a swing-arm to which a coin-pusher of the machine is connected, the other branch of the rocker being normally in contact with coin of a descending column in a coin-tray compartment of said machine, whereby said rocker is tilted to place the lever-branch thereof in track position and further tilted out of contact with said coin coincidental with forward movement of said swing-arm.

50. In testimony that I claim the foregoing I have hereunto set my hand at Watertown 55 in the county of Jefferson and State of Wisconsin in the presence of two witnesses.

EDWARD J. BRANDT.
